CLAIM

The ornamental design for a connector for cylindrical battery, as shown and described.

DESCRIPTION

The present application is also related to U.S. application Ser. No. 29/955,992, filed concurrently herewith, naming inventor Dong Won Yoo and entitled Connector for Cylindrical Battery, and the disclosure of which is incorporated herein by reference.

FIG. 1 is a top front perspective view of a connector for cylindrical battery, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a bottom rear perspective view thereof.

The broken lines of even length depict portions of the connector for cylindrical battery that form no part of the claimed design.
